ATTORNEY

UNITED STATES PATENT OFFICE.

WILLIAM T. HATMAKER, OF DAYTON, OHIO, ASSIGNOR, BY MESNE ASSIGNMENTS, TO THE NATIONAL RECORDING PUMP COMPANY, OF DAYTON, OHIO, A CORPORATION OF OHIO.

LIQUID-DISPENSING PUMP.

Application filed March 12, 1919. Serial No. 282,163.

To all whom it may concern:

Be it known that I, WILLIAM T. HATMAKER, a citizen of the United States, residing at Dayton, in the county of Montgomery and State of Ohio, have invented certain new and useful Improvements in Liquid-Dispensing Pumps, of which the following is a specification, reference being had therein to the accompanying drawing.

10 This invention relates to liquid dispensing pumps. One object of the invention is to provide in connection with such a pump an apparatus which will indicate both the amount of liquid delivered and the price charged for that quantity of liquid.

Another object of the invention is to provide in connection with such a pump an apparatus for making a permanent record of the amount of liquid delivered; and 20 further, to provide such an apparatus which will deliver a sales slip or check showing the amount of liquid delivered.

Another object of the invention is to provide means for setting the pump to cause 25 it to deliver a predetermined quantity of liquid and to then automatically interrupt the operation of the pumping mechanism; and further, to provide means for locking the pumping mechanism against operation until 30 the apparatus has been set.

Other objects of the invention will appear as the mechanism is described in detail.

In the accompanying drawings Fig. 1 is 35 a front elevation partly broken away of a mechanism embodying my invention; Fig. 2 is a side elevation of such mechanism, partly broken away; Fig. 3 is a front elevation of the indicating dials; and Fig. 4 is a vertical section taken centrally through the recording mechanism.

In these drawings I have illustrated one embodiment of my invention and have shown the same as applied to a liquid dispensing apparatus similar to that shown 45 and described in the Patent No. 1,316,032 granted to me Sept. 16, 1919, but it will be obvious that with little or no modification the invention can be applied to dispensing apparatuses of various kinds.

50 The particular dispensing apparatus here shown comprises a double-cylinder double-acting pump in which the operating device moves continuously in a forward direction and the movement of the pistons is auto-

matically reversed at the end of each stroke. 55 I have, however, shown only so much of this mechanism as is necessary to an understanding of the present invention. The cylinders and their pistons are not shown, but each piston is provided with a rack 1, 60 the two racks meshing with the opposite sides of a gear 2, which serves to move the racks, and, consequently, their pistons, simultaneously in opposite directions. The operating mechanism for the gear comprises 65 a shaft 3 which may be provided with a crank or other suitable operating device, not here shown, and on which is slidably mounted a pinion 4 adapted to mesh either with a gear 5 rigidly secured to the gear 2 70 or with an idle gear 6 having secured thereto a second gear 7 which in turn meshes with the gear 2. It will be obvious that the rotation of the shaft 3 and pinion 4 in one direction will serve to rotate the gear 2 in 75 one direction so long as the pinion is in mesh with the gear 5 and will serve to rotate the gear 2 in the opposite direction when the pinion is in mesh with the gear 6. The pinion is automatically shifted from 80 one position to the other at the end of each stroke of the pistons. This mechanism comprises a lever 8 constituting one arm of a bell crank lever and comprising two parts having pins 9 to enter a groove 10 in an 85 elongated hub or sleeve 11 secured to the pinion 4. The other arm of the bell crank lever, which is shown at 12, is connected through the medium of an arm 13 with a lever 14 mounted for movement about the 90 axis of the gear 2 and having parts 15 lying in the path of a stop 16 secured to the gear 5 and adapted to be engaged thereby to impart initial movement to the lever. The connection between the arms 12 and 13 may 95 be of any suitable character. As here shown, the arm 12 carries a pin 112 which lies between two pins 113 on the arm 13. The end of the arm 13 lies between two pins 114, on the arm 14, which are spaced apart 100 to permit of a limited relative movement of the arms. The arm 14 is so arranged with relation to the gear 2 that one or the other of the parts 15 of the arm will be engaged by the stop 16 just before the gear 105 completes its movement in either direction and causes the arm to move with the gear until the arm has passed a position midway

between the limits of its movement, after which the final movement will be imparted to the arm by other means, to shift the pinion 4. As shown in Fig. 1, the gear has just begun its movement which will continue until the stop 16 engages the lower part 15 of the arm 14 and moves that arm to its intermediate position. The lower pin 114 on the arm 14 will not engage the arm 13 until the arm 14 is in an intermediate position and, consequently, this initial movement of the arm 14 will not impart movement to the pinion 4. The final movement is imparted to the lever by a spring 17 connected with the free end of a crank arm 18 which is mounted on a shaft 19 and which is so arranged that the spring 17 will be placed under greater tension as the arm 18 passes a point midway between the limits of its movement and, consequently, as soon as the arm passes this point the spring will become operative and will complete the movement of the arm and of the lever 14, and this movement will cause the pinion 4 to be shifted from one position to the other, and thus reverse the direction of movement of the racks and of the pistons in the cylinders. As has been stated the mechanism so far described forms a part of my Patent No. 1,316,032, and is here shown only for the purpose of explaining the operation of the present invention.

In order to indicate to the customer both the amount of liquid which is delivered to him and the price of that amount of liquid, I have provided a register or indicating device, the operation of which is controlled by the pumping mechanism. As here shown, this indicating device comprises a double scale or fixed indicator, the outer portion 20 of which bears the numerals 0 to 19, and the inner portion 21 of which bears figures indicating the price of each quantity of liquid indicated by the figures on the outer portion of the scale. Any desired unit of measurement may be employed but, in the present instance, the figures on the outer portion of the indicator represent gallons and the figures on the inner portion thereof represent the price computed at 25½¢ per gallon. Inasmuch as the price of any commodity is liable to fluctuation, I have made the inner portion of the fixed indicator removable so that it can be changed as the price changes. As here shown, it consists merely of a disk adapted to fit within the outer circular portion of the fixed indicator, and is provided with openings to receive studs 22 which secure it in position and hold it against rotation. Cooperating with the fixed indicator is a movable indicator which is here shown as a pointer 23 which is rigidly secured to and moves with a shaft 24. The two indicating members may be mounted in any suitable man-

ner. As here shown, the fixed indicator is secured to and forms a part of a plate or member 25, which forms a part of the frame which supports the indicating and recording devices, and is provided with an outwardly extending flange 26 within which the removable disk is arranged. The shaft 24 is journaled in a bearing 27 formed in the frame member 25 and extends rearwardly for some distance beyond its bearing. The shaft 24 may be actuated to impart movement to the movable indicator or pointer by any suitable mechanism which may be controlled by the pumping mechanism. In the present construction a ratchet wheel 28 is rigidly secured to the shaft 24 and is advanced step by step by a pawl 29 mounted for movement about the axis of the shaft 24. This pawl is here shown as pivotally mounted on a plate or arm 30. A detent pawl 31 also engages the ratchet wheel to hold it against rearward movement. The two pawls are acted upon by a spring 32, which extends between them and serves to hold both in engagement with the ratchet wheel, but to permit them to yield and ride over the teeth of the ratchet wheel. The pawl carrying arm 30 may be actuated in any suitable manner, but is here shown as having connected therewith a rod 33 which extends downwardly and is so connected with a moving part of the pumping mechanism that an upward movement will be imparted thereto at the end of each stroke of the piston, thus advancing the ratchet wheel one point for each unit of measurement which, in the present instance, is a gallon, the cylinders each being designed to deliver one gallon of liquid upon each full stroke of the piston. In that form of the device here shown, the arm 33 has its lower end forked as shown at 34 to embrace the shaft 19 of the reversing mechanism for the gear 2, this forked end of the bar serving to support and guide the same. The shaft 19 is provided with suitable means for engaging the bar 33 and imparting upward movement thereto upon each movement of the arm 18, in either direction, thus causing the movable indicator to be advanced one step upon each reversal of the direction of movement of the pistons. It is very desirable in an apparatus of this kind to provide means for making and retaining a permanent record of the amount of liquid dispensed, and it is also desirable that the customer should be provided with a record from the machine itself, showing the amount of liquid which it has delivered. To accomplish this I have provided a recorder adapted to print the record on two strips of paper, or other suitable material, one of which is retained within the machine, and from the other of which the printed portion may be detached and delivered to

the customer. As here shown, this recording mechanism comprises two recording wheels 39 and 40, (Fig. 4) each of which bears on its periphery printing characters 5 or type corresponding to the indications on the outer portion of the fixed indicator 20, and which in the present instance are the numerals 0 to 19. These counter wheels are preferably rigidly connected one to the other 10 and, in the present instance, are shown as formed integral. They are mounted on the shaft 24 and rigidly connected with the ratchet wheel 28 so as to rotate therewith. Means are provided for feeding a strip of 15 paper across the printing point of each counter wheel, 39 and 40. As here shown, the counter wheel 39 prints the permanent record, which is retained within the machine, and the counter wheel 40 prints the sales slip 20 or check. The permanent record is printed on a strip of paper 41 which is taken from a roll 42, and carried about guides 43 and 44 to rewinding drum 45. The sales slip is printed on a strip of paper 46 which is taken 25 from a roll 47 and carried about a guide 48 through a slot 49 in the frame member 25 and indicator disk 21. Interposed between the two strips and the respective counter wheels is an ink ribbon 50 which 30 passes about an actuating drum 51, thence about guides 52 which properly position it with respect to the two printing wheels. Preferably, an inking roller 53 is mounted in engagement with the ribbon to provide 35 the same with fresh ink. The impression may be taken with any suitable apparatus but, as here shown, I have provided platens 54 and 55 to take the impression on the permanent record strips and the sales slip, respectively. These platens are mounted 40 respectively on the ends of arms 56 and 57 which are pivotally mounted at their opposite ends and which are provided with 45 projections or noses 58 and 59 adapted to be engaged by a double cam 60. A spring 61 extends between the two arms and tends to move the platens toward the type wheels, but when the cam 60 is in its normal or idle position, the high points thereof will 50 be in contact with the projections on the platen arms and will hold the latter in their outermost or separated positions. Upon forward movement being imparted to the cam, the high portions thereof will clear 55 the projections on the respective platen arms and permit the platens to be moved inwardly by the spring 61, which will result in an impression being taken from each type wheel. This cam may be operated in any 60 suitable manner but, as here shown, I have connected therewith an actuating shaft or rod 62 which extends rearwardly from the recording devices and through the wall of the casing, where it is provided with 65 an angular head 63 to receive an actu- ating key or handle. The record strips may be advanced in various ways, but I prefer to advance the permanent record strip by the operation of the platen arm 56 and, to this end, I have provided the 70 rewinding drum 45 with a ratchet wheel 64 with which cooperates a pawl 65 carried by an arm or pawl carrying plate 66 journaled on the axis of the drum and connected with one end of a link 67, the 75 opposite end of which is connected with an arm 68 which, in the present instance, is pivoted on the shaft which carries the roll 42 and has connected therewith a second arm 69 which is connected with a rock arm 70 80 mounted on the axis of the platen arm 56 and rigidly connected therewith. The arrangement is such that the operative movement of the platen arm, that is, the movement of the platen into engagement with 85 the type wheel, will cause the pawl 65 to be retracted and, as the platen arm is restored to its normal or idle position by the cam 60, the pawl will be moved forward and the ratchet wheel and the drum 45 advanced, thus feeding the paper forward. The ribbon 50 is here shown as actuated in 90 the same manner and from the same mechanism. The ribbon drum 51 is provided with a ratchet wheel 71, with which cooperates a spring-pressed pawl 72 carried by an arm 73, which is connected by a link 74 with the plate or pawl carrying arm 66 of the rewinding drum 45. Consequently, the 95 ribbon will be fed forward upon each forward movement of the record strip. In the particular construction here shown, I have not provided any automatic feed for the sales slip, but this may be drawn out by hand and torn off. Obviously, however, an 100 automatic feed can be applied thereto if so desired. 105

To prevent the movement of the pumping mechanism from being continued after the full quantity of liquid has been delivered to the customer, I have provided controlling means for the pump mechanism, which may be set to cause the operation of the pump to be automatically interrupted when a pre-determined quantity of liquid has been delivered. I also prefer that this mechanism shall be of such a character as to positively lock the pumping mechanism against operation until the device has been so set. This device may take various forms but, as here shown, it comprises a rotatable member 110 which is preferably in the form of a disk 75 and is rotatably and slidably mounted on the end of the shaft 24, which carries the counter wheels 39 and 40. The face of the disk 75 lies substantially parallel with and adjacent to the face of the counter wheel 39 and is held normally in this position by means of a spring 76 coiled about the end of 115 the shaft 24 within the hollow hub 77 of the 120 shaft 24. 125

130

disk and confined between the closed end of said hollow hub, and a head 78 on the shaft 24. The rotatable member 75 has rigidly secured thereto a pin 79 adapted to extend 5 into any one of a series of recesses 80 formed in the adjacent face of the counter wheel 39 and arranged in annular series, there being one of these recesses for each type face on the counter wheel. Connected with the rotatable member 75 is a rod or shank 81 extending outwardly through an opening in the casing and provided with a handle 82, by means of which the rotatable member or disk 75 may be drawn outwardly to disengage 10 the pin 79 from the counter wheel, and then rotate it to cause the pin to engage the recess in the counter wheel adjacent to the numeral or type face corresponding to the number of gallons of liquid it is desired to deliver. 15 The position of the pin 79 with relation to the counter wheel is indicated by a pointer 83 connected with the handle 82 and travelling over a scale on the wall of the casing, which is not here shown. Preferably the 20 handle and its shank 81 are removably connected with the elongated hub 77 of the rotatable member so that the handle may be disconnected therefrom when the pump is not in use. The disk 75 has formed in the 25 periphery thereof a notch 84 adapted to receive a yieldable detent 85 when the disk is in its normal or idle position, that is, when the pointer 83 indicates zero. Consequently, when a customer wants a certain amount of liquid, say, ten gallons, the 30 handle 82 will be manipulated to disconnect the rotatable member from the counter wheel and to set the pointer 83 at 10, the detent 85 yielding to permit of the rotation 35 of the disk or rotatable member. The pumping mechanism is then operated to cause the liquid to be delivered and when the counter wheel 39 has been advanced ten spaces the notch 84 in the rotatable member 40 75 will again be brought into alignment with the yieldable detent, which will enter the notch and thus check the movement of the rotatable member. The detent may be 45 of such a character either to positively lock the device against further movement, or it may temporarily check the movement of the rotatable member so that greater force must be applied thereto before the movement can be continued, and thus indicate to 50 the operator that the measurement has been completed. I prefer, however, to provide means controlled by this yieldable detent for positively locking the pumping mechanism against further movement, and which 55 may be of such a character as to prevent the initial operation of the pumping mechanism until the predetermining device has been set. To accomplish this, I have mounted 60 on the operating shaft 3 of the pumping mechanism a ratchet wheel 86, with which 65

engages a pawl 87 pivotally mounted at 88 and acted upon by a spring 89 to hold it normally in engagement with the ratchet wheel 86. Connected with the pawl 87 and arranged on the opposite side of its axis is 70 a finger 90 which engages a second finger 91 pivotally mounted at 92 and rigidly connected with an arm 93 which is also mounted on the axis 92 and which carries the yieldable detent 85, the latter being in the 75 form of a pin or roller extending transversely from the end of the arm 93. The arrangement of the parts is such that when the mechanism is in its normal or idle position and the detent 85 lies in the recess 80 84 of the rotatable member 75, the pawl 87 will be in engagement with the ratchet wheel 86 and the forward movement of the operating mechanism will be positively prevented. When the rotatable member is actuated to set the predetermining device, the detent or roller 85 will ride out of the notch onto the periphery of the rotatable member, thus rocking the arm 93 and the finger 91 about their axes and causing said 85 finger to engage the finger 90 and thus move the pawl 87 against the tension of its spring and out of engagement with the ratchet wheel 86, thereby releasing the shaft 3 for 90 operation. When the predetermined quantity of liquid has been delivered, the detent 85 will again be opposite the notch 84 and the action of the spring 89 will serve to move the detent into the notch as well as to move the pawl 87 into engagement with 95 the ratchet wheel 100

The operation of the mechanism as a whole will be readily understood from the description of the several parts thereof, and it will be apparent that I have provided in connection with a dispensing pump, an apparatus which will indicate to the customer both the quantity of liquid delivered and the price of that liquid; and further, that this apparatus will make a permanent 105 printed record of the amount of liquid delivered, which record will be retained within the casing of the pump, and that at the same time a sales check or slip will be printed which may be detached and delivered to the customer. It will also be apparent that I have provided in connection with this apparatus a predetermining device which must be set before the pump can be operated and which will automatically interrupt the 110 movement of the pumping mechanism when the predetermined quantity of liquid has been delivered; and further, that this predetermining mechanism is of such a character that initial movement cannot be imparted 115 to the pumping mechanism until the predetermining device has been set.

While I have shown and described one embodiment of my invention, I wish it to be understood that I do not desire to be 120 125 130

limited to details of construction, as obvious modifications will occur to a person skilled in the art.

Having thus fully described my invention, what I claim as new and desire to secure by Letters Patent is:

1. In a register for dispensing apparatus, a printing counter, means controlled by said dispensing apparatus for actuating said printing counter, means for supporting a strip of paper adjacent to said printing counter, a platen to take an impression from said printing counter on said paper, means for actuating said platen, and means controlled by said operation of said platen for advancing the paper.

2. In a register for dispensing apparatus, a printing counter, means controlled by said dispensing apparatus for actuating said printing counter, means for supporting a strip of paper adjacent to said printing counter and comprising a feeding device, an ink ribbon interposed between said paper and said printing counter and means for actuating said ink ribbon, a platen, means for actuating said platen to cause an impression to be taken from said printing counter on said paper, and means controlled by said operation of said platen to actuate said paper feeding device and said ribbon actuating device.

3. In a register for dispensing apparatus, a printing counter, means controlled by said dispensing apparatus for actuating said printing counter, means for supporting a strip of paper adjacent to said printing counter and comprising a feeding device, an ink ribbon interposed between said paper and said printing counter and means for actuating said ink ribbon, a platen, a rock arm to support said platen, a second arm connected with said rock arm, a bell crank lever having one arm connected with said second arm, and a link connected with the other arm of said bell crank lever and with said paper feeding device.

4. In a register for dispensing apparatus, a printing counter, means controlled by said dispensing apparatus for actuating said

printing counter, means for supporting a 50
strip of paper adjacent to said printing
counter and comprising a feeding device, an
ink ribbon interposed between said paper
and said printing counter, means for
actuating said ink ribbon, a platen, a rock 55
arm to support said platen, a second arm
connected with said rock arm, a bell crank
lever having one arm connected with said
second arm, a link connected with the other
arm of said bell crank lever and with said
paper feeding device, and a second link to
connect said paper feeding device with said
ribbon actuating device. 60

5. In a register for dispensing apparatus, a printing counter, means controlled by said dispensing apparatus to cause said counter to record the amount of liquid delivered, a disk arranged adjacent to said printing counter having a notch in the periphery thereof, means for connecting said disk with said printing counter in different positions relatively thereto and for causing said disk to rotate with said counter when the latter is actuated, and a part adapted to enter said notch in said disk when the latter is in a predetermined position. 65 70 75

6. In a register for dispensing apparatus, a printing counter, means controlled by said dispensing apparatus to cause said counter to record the amount of liquid delivered, a disk arranged adjacent to said printing counter and having a notch in the periphery thereof, means for connecting said disk with said printing counter in different positions relatively thereto and for causing said disk to rotate with said counter when the latter is actuated, a part adapted to enter said notch in said disk when the latter is in its normal position, a normally operative locking device for said dispensing apparatus, and an operative connection between said locking device and said part whereby the locking device will be rendered inoperative when said part is moved out of said notch. 80 85 90

In testimony whereof, I affix my signature hereto. 95

WILLIAM T. HATMAKER.
